United States Patent Office

Des. 214,629
Patented July 8, 1969

214,629

RADOME

Fred H. Bargetzi, Huntington, Herbert T. Heinlein, Centereach, and Charles L. Loesch, Massapequa, N.Y., assignors to Sperry Rand Corporation, Great Neck, N.Y., a corporation of Delaware

Filed Sept. 25, 1968, Ser. No. 13,703

Term of patent 14 years

Int. Cl. D14—99

U.S. Cl. D26—14

FIG. 1.

FIG. 2.

FIG. 3.

FIG. 1 is a perspective view of the front and right side of a radome showing our new design;

FIG. 2 is a top plan view thereof; and

FIG. 3 is a bottom plan view thereof.

The left side of the radome is a mirror image of the side shown in FIG. 1.

We claim:

The ornamental design for a radome, as shown and described.
